(57) **CLAIM**

The ornamental design for an advertising and image display device, as shown and described.

DESCRIPTION

FIG. 1 is an orthogonal view illustrating an advertising and image display device in accordance with the present invention;

FIG. 2 is a top view of the advertising and image display device of FIG. 1;

FIG. 3 is a side view of the advertising and image display device of FIG. 1;

FIG. 4 is a front view of the advertising and image display device of FIG. 1;

FIG. 5 is a back view of the advertising and image display device of FIG. 1; and,

FIG. 6 is a bottom view of the advertising and image display device of FIG. 1.

In the drawings, the broken lines represent environmental structure forming no part of the claim.
